FRANK JUHASZ, OF WAUKEGAN, ILLINOIS, ASSIGNOR OF ONE-HALF TO HELEN JUHASZ, OF WAUKEGAN, ILLINOIS.

SOUNDING TOY.

993,380.

Specification of Letters Patent. Patented May 30, 1911.

Application filed June 10, 1910. Serial No. 566,262.

To all whom it may concern:

Be it known that I, FRANK JUHASZ, a citizen of the United States, residing at Waukegan, in the county of Lake and State of Illinois, have invented certain new and useful Improvements in Sounding Toys; and I do hereby declare the following to be a full, clear, and exact description of the invention, such as will enable others skilled 10 in the art to which it appertains to make and use the same.

This invention relates to sounding toys; and it consists in the novel construction and combination of the parts hereinafter fully 15 described and claimed.

In the drawings, Figure 1 is a side view of the toy showing the base in section. Fig. 2 is a cross-section taken on the line $\alpha-\alpha$ in Fig. 1.

20 A is the base of the toy which is formed of a hollow box having a top B which forms a sounding-board. A bar C is secured longitudinally in the box under the sounding-board at its middle part, and this bar is 25 preferably formed of wood and its ends are secured to the ends of the box.

D is an anvil or sounding-block provided with a flange d at its top which rests on the sounding-board. The main portion of the 30 anvil projects downwardly through a hole in the sounding-board, and it has a forked portion d' at its lower end which straddles the middle part of the bar C and which is secured to the said bar.

35 E are two strikers preferably shaped roughly to conform with the outline of the human frame, and having forked lower end portions or legs e which straddle the bar C and which are pivoted to the said bar by 40 pins e'.

F are holes in the sounding-board, arranged one at each end of the anvil, and the upper parts of the strikers project through these holes. The strikers E are provided with projecting arms or hammers f which 45 extend laterally over the anvil.

G is an operating-rod pivoted by pins g to the lower end portions of the legs e, and which is slideable in a guide-hole g' in one end of the box A. 50

The toy is operated by reciprocating the projecting end portion of the rod G by hand. This causes the strikers to hammer alternately upon the anvil in imitation of two blacksmiths at work, and in imitation 55 of the sound commonly heard in a blacksmith's shop.

What I claim is:

In a sounding toy, the combination, with a supporting sounding-box provided with 60 a hole in one of its ends and having at its top a sounding-board provided with holes, of a bar secured to the ends of the box, an anvil having at its top a flange which rests on the sounding board and having a stem 65 which passes through one of the holes in the sounding-board and is secured to the said bar, two strikers pivoted to the said bar and projecting through two of the holes in the sounding-board and provided with 70 hammers for striking the anvil, and an operating-rod pivoted to the lower parts of the strikers inside the box and projecting through the hole in the end of the box. 75

In testimony whereof I have affixed my signature in the presence of two witnesses.

FRANK JUHASZ.
